2 Sheets-Sheet 2

UNITED STATES PATENT OFFICE.

JOHN D. LOOP, OF LONG BEACH, CALIFORNIA.

WHALE-HARPOONING APPARATUS.

Application filed February 16, 1920. Serial No. 358,851.

To all whom it may concern:

Be it known that I, JOHN D. LOOP, a citizen of the United States, residing at Long Beach, in the county of Los Angeles and 5 State of California, have invented new and useful Improvements in Whale-Harpooning Apparatus, of which the following is a specification.

This invention relates to aerial apparatus 10 for whaling and has for its object to provide means for harpooning whales, and the invention consists of an aerial machine having harpooning means and means for controlling the discharge of the same, so as 15 to facilitate the ready location of whales and their capture and subsequent dispatch.

An embodiment of the invention is illustrated in the accompanying drawings and described and claimed hereinafter.

20 Figure 1 is a perspective showing the use of the apparatus in the harpooning of a whale.

Fig. 2 is a side elevation of a hydro-aeroplane provided with the harpoon carrying and discharging means.

Fig. 3 is a diagrammatic perspective showing a portion of the gondola and illustrating in detail a form of harpoon releasing.

30 Fig. 4 is an end elevation of the harpoon supported on the carrying means provided on the airplane.

Fig. 5 is a side elevation of the combined harpoon and buoy.

35 Fig. 6 is a sectional detail view taken longitudinally of the connecting means between the harpoon and contiguous end of the buoy.

Fig. 7 is a perspective of a fragment of 40 a connecting pin.

Fig. 8 is an end view of a buoy showing the tail blades.

The present invention is designed to provide an efficient means for greatly facilitating the location of whales or other objects at sea and in water, and for enabling the efficient shooting or capture of the same so that they may be subsequently dispatched or taken to remove the valuable parts thereof, 45 as in ordinary whaling practices, and to this end the invention is preferably incorporated in the combination of an airplane

or a hydro-aeroplane, one form of which is generally designated at A and the frame structure thereof is shown as including in 55 this case a gondola 2 from which extends a set of spars or braces 3 connecting, for instance, with the lower frame 4 of the wing structure. A harpoon, a form of which is shown clearly in Fig. 5 at H, is designed to 60 be detachably connected, for instance, to the spars or braces 3 so that the harpoon can be readily directed toward and released to strike a whale indicated at W.

The harpoon is combined with a buoyant 65 member, as a spool S, so that after the harpoon has been embedded in the whale the spool or floating buoy S will serve to indicate the location of the whale after the 70 huntsmen in the airplane have succeeded in shooting or capturing him and may pass on in the hunt.

The harpoon has a suitable point 5 and a shank 6 with a cross piece 7 at its hilt 8, which latter is shown in an enlarged portion having a socket chamber 9 into which there is extended a connecting pin 10. This pin has a notch or shoulder 11 designed to engage a frangible tooth or locking member 12 having a weakened shank portion 80 13, the extending end of the shank 14 being suitably connected or bound to a sleeve 15 fastened as by a flanged collar 16 to the head 17 of the spool or buoy S. The sleeve 15 extends centrally into the head 17 of the 85 buoy and the notch or shoulder 11 is so located that when it is engaged by the latch 12 the end of the pin 10 extending into the sleeve 15 is spaced from the inner end of the sleeve so that the pin is capable of further 90 inward movement.

Attached to the hilt of the harpoon is a substantial rope or other flexible device 18 and a slack length of this extends rearwardly to the reduced body of the spool or 95 buoy S on which it is wound, as shown in Figs. 5 and 6; and the opposite end of the buoy rope 18 is permanently secured to the buoy. To prevent the unravelling or working loose of the coils of the rope 18 the end 100 of it passing over the head 17 is bound down by a cord or small piece of rope 19 tied around the rope, as at 19^a and thence passing through an eye 20 in the head 17. The

opposite end of the fastening cord or rope 19 is shown as tied or bound around the weakened portion 13 of the shank 14 just beyond the head or latch part 12.

5 The thus assembled harpoon and buoy with the parts as shown in Fig. 6 is attached to the airplane by suitable carrying and releasing means and a form of which is shown in Fig. 3 as comprising a pair of 10 endless ropes or belts which are shown at 21, the ropes or belts having a bight 21^a passed around the spars 3 and then each 15 of the belts is coiled around the buoy which is shown in dotted lines at S, with the opposite or free end 21^b passed between the bight 21^a of its respective belt and projected sufficiently beyond to form a loop to receive any suitable suspending and dropping or releasing device, such for instance, 20 as a pole, rod, or support 22.

To operate the releasing rod or means 22 a belt cord or other suitable device 23 is attached to the same and this is led to within 25 convenient reach of the pilot or huntsman in the airplane so that upon the location of a whale when the airplane is brought into the desired position, the huntsman can by pulling on the control cord or rope 23 secure the operation of the releasing device 30 or rope 22 and by releasing the bights 21^b of the suspending belts or ropes 21 the harpoon with its attached buoy S is quickly released and may be projected into the direction of the whale. The rear bight is released first to allow a guide tail on the rear portion of the buoy to be sufficiently clear of the wing of the aeroplane before releasing the forward bight. In the course of the 35 flight the combined harpoon and buoy will be immediately brought to the normal flying position due to the action of the guide tail.

When the harpoon enters the whale the 40 resistance is such as to force the pin or connecting member 10 back endwise in the sleeve with the result that the notched wall or shoulder 11 tilts the head 12 of the latch rearwardly, and causes the breaking of the 45 weakened part 13 of the shank 14 and disconnects the binding cord 19, and therefore, 50 when the whale plunges the harpoon is withdrawn with the pin 10 and the rope 18 attached to the harpoon begins to unwind from its spool or buoy S, this being permitted by the now free cord 19 which freely 55 runs back through the eye 20 in the head 17 of the spool.

From this it will be seen, therefore, that 60 after the whale has been struck by the harpoon the location of the whale can be readily determined by reason of the floating buoy S which serves as a plain signal to those following the huntsmen in the airplane and whose duty it is to secure the whale, as in the ordinary practice of whaling.

To facilitate the direction of the flight of the harpoon with the combined buoy, the latter may have on its trailing or rear end a guide means in the form of a tail comprising in the present case a diametrically arranged blade 25 and a radially arranged blade 26 extending perpendicular thereto, as shown in Fig. 8.

It is understood that this device may be used in combination with any form of aerial 75 vessel as may be desired and is not limited to use with an air-plane, which is illustrated for example only.

What is claimed is:

1. An aerial harpoon comprising a penetrating member and a buoyant member attached thereto, means for disconnecting the buoyant member from the harpoon when the latter has struck the target; and a flexible connection attached to the buoyant member and connected to the harpoon, the flexible member comprising a rope wound on the body of the buoyant member, and means for securing the wound rope against 85 unwinding until the harpoon has struck. 90

2. An aerial harpoon comprising a buoyant member, a penetrating member slidably associated with the buoyant member, a frangible tooth sustained on the buoyant member and engaging the penetrating member in a partly projected position with respect to the buoyant member, and means whereby the penetrating member may be forced inwardly of the buoyant member to cause said tooth to release the penetrating 100 member. 95

3. An aerial harpoon comprising a buoyant member, a penetrating member, a connecting pin slidably associated with the buoyant member and connected to the penetrating member, a notch formed in the connecting pin, a frangible tooth carried by the buoyant member and engaging within said notch for maintaining the connecting pin in a partly projected position with respect to the buoyant member, a flexible member connected to the penetrating member and trained about the buoyant member, and a second flexible member connected to the first flexible member and to the frangible tooth 110 for the purposes described. 115

4. An aerial harpoon comprising a penetrating member, a buoyant member connected thereto, means for disconnecting the buoyant member from the penetrating member when the latter has struck a target, a flexible connection attached to the buoyant member and connected to the penetrating member, and means for securing the flexible connection against disengagement from the buoyant member until the penetrating member has struck. 120

5. An aerial harpoon comprising a penetrating member, a second member connected thereto, a flexible member trained about the 130

second member, and connected to the penetrating member, and means for securing the flexible member against unwinding from the second member until the penetrating member has struck a target.

6. An aerial harpoon comprising a buoyant member, a penetrating member movable on the buoyant member, means for disen-

gaging the buoyant member from the penetrating member, and means for limiting the 10 penetrating movement of the penetrating member, the last means being operable to render the disengaging means active.

In testimony whereof I have signed my name to this specification.

JOHN D. LOOP.
